United States Patent Office.

REINHOLD BOEKLEN, OF BROOKLYN, NEW YORK.

Letters Patent No. 64,623, dated May 14, 1867; antedated May 3.

BLOTTING-PAD.

The Schedule referred to in these Letters Patent and making part of the same.

TO ALL WHOM IT MAY CONCERN:

Be it known that I, REINHOLD BOEKLEN, of the city of Brooklyn, in the county of Kings, and State of New York, have made certain new and useful Improvements in Blotters; and I hereby declare that the following is a full, clear, and exact description of the construction and operation of the same, reference being had to the annexed drawings, forming part of this specification, in which—

Figure 1 represents a side view of my improved blotter.

Figure 2 is a top view of the same.

Figure 3, a vertical section, the plane of section being indicated by the line xx in fig. 1.

Figure 4 represents a side view of a modification of the same.

Similar letters of reference indicate corresponding parts in the several figures.

The nature of this invention consists, first, in the employment of an elastic or pressing bottom to the blotter, whereby the same is allowed to yield and conform itself to the pressure and surface to which it is applied; second, it consists in the employment of slides to work on inclined planes, formed on each end of the blotter-plate, whereby the appearance and construction of the blotter is improved and simplified, and the blotting-paper more perfectly drawn tight over the ends of the blotter-plate than with those heretofore known or used.

To enable others skilled in the art to make and use my invention, I will proceed to describe its construction and operation.

A represents the blotter-plate or board, to which the blotting-papers are attached, and its top face is provided with a handle or knob, B, which is permanently secured to it. Each of the ends of this board A are finished taper or wedge-shaped, as shown in figs. 1 and 4, and its central portion is cut thin, so as to allow the board to yield or spring, and conform itself to a somewhat curved surface when pressure is applied on the handle B. The sides of the ends of the wedge-shaped parts of the board are provided with grooves or shoulders, C C, and metal slides D D, which are fitted over the top of the ends, so as to reach and fit into the grooves or over the shoulders C C, and serve to secure the blotting-paper to the board, so that, as the blotting-paper is wasted, and sheet after sheet thrown aside, the remaining sheets are readily secured again by forcing the slides more tightly on the inclined plane. Instead of making the board A so as to yield or spring, a separate flexible board of rubber or other material, instead of the board A, may be used, as shown in fig. 4.

From the foregoing it may be seen that by means of the flexible blotter-board, the blotter, when used, will readily yield to the surface applied to, and thereby the whole of the surface of the same is made use of, and by means of the slides D D operating on inclined planes the blotting-paper is more tightly drawn over the ends of the blotter-board than with those made heretofore.

What I claim as my invention, and desire to secure by Letters Patent, is—

1. The employment or use of a flexible board or bottom to the blotter, operated and for the purpose substantially as herein described.
2. The employment of the slides D D, combined with the wedge-shaped ends of the blotter-board A, operated and for the purpose substantially as herein shown.

REINHOLD BOEKLEN.
